UNITED STATES PATENT OFFICE.

CARRINGTON W. GARRETT, OF WASHINGTON, DISTRICT OF COLUMBIA.

POST-HOLE DIGGER.

1,192,884.

Specification of Letters Patent.

Patented Aug. 1, 1916.

Application filed July 17, 1914. Serial No. 851,502.

To all whom it may concern:

Be it known that I, CARRINGTON W. GARRETT, a citizen of the United States, residing at Washington, in the District of Columbia, 5 have invented certain new and useful Improvements in Post-Hole Diggers; and I do hereby declare the following to be a full, clear, and exact description of the invention, such as will enable others skilled in the art to 10 which it appertains to make and use the same.

This invention relates to post-hole diggers of the type utilizing endless belt excavators.

An object in view is the provision of 15 means for economical use of hand power for effecting a maximum of excavation with a minimum expenditure of energy.

A further object is the rendering of the 20 parts simple and compact in structure and assemblage, for enabling handling and transportation.

With these and other objects in view, as 25 will in part be stated and in part become apparent, the invention comprises certain novel constructions, combinations and arrangements of parts as will hereinafter become obvious.

In the accompanying drawing,—Figure 1 is a vertical, central section taken longitudinally through an apparatus embodying the 30 features of the invention, intermediate portions being broken out for the saving of space. Fig. 2 is a view in side elevation thereof. Fig. 3 is a fragmentary, enlarged 35 cross section taken on the plane indicated by line 3—3 of Fig. 1 and looking downwardly. Fig. 4 is a fragmentary plan of one of the frame guides.

Referring to the drawing by numerals, 40 1, 1 indicate the upright bars of a frame which is completed by a block 2 fixed to and connecting the upper ends of rods 1, and block 3 fixed to and connecting the lower ends of rods 1. Blocks 2 and 3 are preferably 45 castings and are rigidly fixed to the rods 1 so as to form a rigid sustaining frame, which is arranged to slide vertically in a guiding frame consisting of supporting legs 4, 4, resting on the ground and connected at 50 their upper ends to a table 5, the table having an annular L-plate connected by cross plates 6 and 29. Plate 29 is provided with vertical, preferably integral, flanges 7 and a guiding aperture 8, one aperture 8 being 55 formed for each rod 1, for guiding the sustaining frame in its movement and prevent-

ing lateral or edgewise play thereof. Legs 4 are each detachably connected to the table by having an offset shoulder disposed beneath the table and an upturned tongue 4' 60 extending through an aperture 4'' in the plate 6 or directly engaging table 5. A bolt 5', extending through the table and the offset shoulder, completes the detachable connection of each leg with the table, and the 65 legs are preferably braced by stays 9 detachably connected to the respective legs and all detachably connected to a central sleeve 10. Lateral brackets 9' are fixed to two of the stays 9, and each terminates in a sleeve 9'' 70 surrounding the respective rod 1 for co-operating with guiding apertures 8 in guiding the sustaining frame in its vertical movement.

Block 2 carries a shaft 11, the projecting 75 end portions of which form journals for drums 12, 12, each of which is engaged by a conveyer belt 13, of any appropriate type, but each consisting preferably of a pair of endless sprocket chains extending from the 80 respective drums 12 to and about corresponding drums 14 arranged at the lower end of the sustaining frame and journaled on stub shafts 15, 15, detachably fixed to the block 3. In view of the employment of 85 sprocket chain belts, drums 12 and 14 are, of course, formed with appropriate sprocket teeth intermeshing with the chains. Drums 14 are spaced apart only a distance sufficient 90 to enable the extension of bars 1 therebetween without contact, and the drums are internally hollow to accommodate block 3 and gearing to be described. The walls of the hollowed interior of each drum are flared to form an incline 14' for dirt to roll down 95 for automatically keeping the interior of the drums clear during use. Each drum 14 may be journaled directly on shaft 15, but preferably a beveled gear 16 is provided for each shaft 15 and is formed with an axial sleeve 100 16' journaled on the respective shaft. On the extended portion of each sleeve 16', the respective drum 14 is keyed. Horizontally disposed beveled gear 17 meshes with the two gears 16, and an actuating shaft 18 extends throughout the sustaining frame and through gear 17 for transmitting power to the gear, the gear being keyed to the shaft. Shaft 18 is formed transversely square, as seen in Fig. 3, for the greater portion of its 105 length, but at its upper end is cylindrical and journaled in block 2, and at its lower

end is cylindrical and extends through and is journaled in block 3. The lower cylindrical portion of shaft 18, below gear 17 and above block 3, is provided with an annular flange 18' resting upon thrust bearings 19, the latter being preferably balls and confined by retainer ring 20, the balls finding a raceway on the upper portion of block 3. A dust and dirt guard is provided for gears 16 and 17, and consists of a housing or casing 21 preferably of sheet material. Each drum 14, at its inner face, is formed with an annular flat portion or race-way 22, and rollers 23, 24, carried by shaft 18 and disposed at diametrically opposite points of the race-ways engage the race-ways 22 for limiting tilting stresses and lateral play of rollers 14.

Each drum 14 has its periphery provided with a number of radial digger teeth 23', preferably having their free end portions bent at various angles at different places about the periphery of the respective drums, so as to insure engagement of substantially all earth beneath the drums by the teeth when the drums are revolved. As this staggered relation of the teeth terminals could not be accurately delineated except by an extension and then only by a distortion of the curved surfaces of the peripheries of the drums, the staggered relation of the teeth terminals has been indicated by the dotted lines in Fig. 1.

Detachably fixed to the central portion of plates 6 and 29 is a socket bearing 24' which is centrally apertured for freely accommodating shaft 18, and a cone bearing 25 rides in socket 24' and is also centrally apertured for free passage of shaft 18. Cone 25 is detachably fixed to a beveled gear 26 which meshes with like gears 27 which latter are keyed to stub shafts 28 engaged by and adapted to be manually actuated by crank 28'. Each shaft 28 is journaled at its inner end in a bracket 29'' fixed to the central portion of plate 29, and extending across table 5 between gears 27, the plate 29 being appropriately apertured to freely accommodate shaft 18. The outer portion of each shaft 28 is journaled in a bracket 30 fixed to and upstanding from the respective side of the table 5.

Cone bearing 25 has a central aperture of sufficient size to freely accommodate shaft 18, which, as seen in Fig. 3, is squared at the places of engagement of cone 25, and, to eliminate friction due to relative movement of the shaft, cone 25 is provided with rounded lateral recesses opening into the central aperture and disposed to receive roller bearings 25', there being one roller 25' for each side of shaft 18. As the rollers 25' are confined against longitudinal movement relative to either the cone or the shaft, the shaft 65 must rotate when the cone is rotated, and

yet the shaft is free for vertical, longitudinal movement with a minimum of friction.

Each endless belt carries a series of elevator buckets 31 of a size to be accommodated between the rows of teeth 23', and a spring 32 is fixed to block 2 with its end portions extending into the path of the inner ends of buckets 31 so that, in operation, the buckets strike the spring and sufficient vibration is imparted to the buckets as they pass over drums 12 to insure discharge of the contents of the buckets as they pass over the respective drums, the angle of the buckets being such at the time of the discharge as to insure falling of the discharged dirt outside of the excavation being made.

The operation is believed to be obvious, but may be briefly stated, consisting merely of manually or otherwise rotating shafts 28 in a direction causing travel of the endless conveyor belts 13 in the direction indicated by the arrow in Fig. 2. Drums 14 are thereby revolved through power transmitted through shaft 18 and gears 17 and 16, so that the teeth 23' loosen the dirt and the buckets remove it. As this continues, the drums descend along with the sustaining frame and parts sustained thereby. Bars 1 and shaft 18 are guided in their vertical descent and thus insure straight downward movement of the drums and a resulting vertical post-hole.

What I claim is:—

1. In a post-hole digger, the combination of upright rods and upper and lower blocks 100 fixed thereto, a retaining frame having vertically disposed sleeves surrounding and guiding said rods, a shaft journaled in the blocks, a drum rotatably carried by the lower block, a drum rotatably carried by the upper block, an endless conveyor belt operatively extended about the drums, excavating means projecting from the lower drum, means for rotating the shaft, means for transmitting movement from the shaft 110 to the lower drum, and conveying means carried by the belt.

2. In a post-hole digger, the combination of a vertically shiftable sustaining frame, a retaining frame guiding the sustaining frame in its movement, a squared shaft journaled in the sustaining frame and shiftable longitudinally therewith, a bearing member sustained by the retaining frame and having an aperture through which the shaft is 120 adapted to move, said bearing having recesses laterally of the shaft, roller bearings in said recesses contacting with the faces of the shaft and confined against longitudinal movement relative to the bearing member, 125 means for revolving the bearing member, and excavating means driven by the shaft.

3. In a post-hole digger, a vertically movable sustaining frame, means guiding the frame in its movement, a shaft journaled in 130

the frame, means for rotating the shaft, a pair of drums disposed on opposite sides of the shaft, gearing actuated by the shaft for driving the drums, and rollers carried by the 5 shaft and engaging the inner ends of the drums for steadyng movement thereof.

4. In a post-hole digger, excavating rollers internally hollow and having their interior walls flaring to provide inclines down 10 which dirt is adapted to move to be discharged from within the rollers, and driving means for the rollers within the hollow portions thereof.

5. In a post-hole digger, the combination 15 of guiding rods, means for guiding the rods,

a block fixed to the rods, shafts fixed to the block, a gear wheel journaled on each shaft, an actuating shaft journaled in the block, a gear wheel actuated by said last-named shaft and meshing with the first-named gear 20 wheels, and drums fixed to the first-named gear wheels and substantially inclosing all of the gear wheels.

In testimony whereof I affix my signature in presence of two witnesses.

CARRINGTON W. GARRETT.
